UNITED STATES PATENT OFFICE.

WALTER E. EGGINTON, OF CORNING, NEW YORK.

DESIGN FOR A GLASS DISH OR SIMILAR ARTICLE.

No. 39,051.

Specification for Design.

Patented Feb. 4, 1908.

Application filed November 14, 1907. Serial No. 402,212. Term of patent 7 years.

To all whom it may concern:

Be it known that I, WALTER E. EGGINTON, a citizen of the United States, residing at Corning, in the county of Steuben and State of New York, have invented a new, original, and ornamental Design for Glass Dishes or Similar Articles, of which the following is a specification, reference being had to the accompanying drawing, forming part thereof.

The figure is a plan view of a glass dish showing my new design.

I claim:

The ornamental design for a glass dish or similar article, as shown.

WALTER E. EGGINTON.
